UNITED STATES PATENT OFFICE.

GEORGE L. PHILLIPS, OF ROCHESTER, NEW YORK.

ROD-PACKING.

1,142,980.

Specification of Letters Patent.

Patented June 15, 1915.

Application filed April 9, 1913. Serial No. 760,011.

To all whom it may concern:

Be it known that I, GEORGE L. PHILLIPS, a citizen of the United States, residing at Rochester, in the county of Monroe and 5 State of New York, have invented new and useful Improvements in Rod-Packings, of which the following is a specification.

The present invention relates to rod packings and more particularly to that type used 10 in connection with fluid pressure apparatus as steam and gas engines, air compressors and similar apparatus.

An object of the invention is to provide 15 an auxiliary packing device which is normally out of packing relation with the rod but which may be brought into packing relation when desired without stopping the operation of the apparatus.

To this and other ends the invention consists 20 in certain parts and combinations of parts all of which will be hereinafter described, the novel features being pointed out in the appended claims.

In the drawings: Figure 1 is a longitudinal 25 sectional view of the invention applied, Fig. 2 is a fragmentary view showing the operating steam connections and vent.

There is illustrated a fragment of a boiler shell 10 apertured for the passage of the stem 11 which is of the ordinary plain cylindrical form, the usual form of packing box 12 being fitted therearound. Secured to the inner side of the shell there is a cylinder 13 having a flange base 14 bolted steam tight 30 to the shell. Suitable gaskets 15 are confined between the packing box and the shell and between the cylinder 13 and the shell. The cylinder 13 at its outer end is provided 35 with an inturned flange 16, serving as a stop, for a purpose to be described. A piston 17 is engaged slidably on the stem 11 within the cylinder, being properly fitted to the latter and having packing rings 18 thereon. At its inner end toward the box 12, the 40 piston is provided with a ground conical seat 19 in which there is adapted to seat the adjacent end of a sliding valve collar 20 engaged around the stem, this and the piston being freely and independently movable 45 on the stem. Secured to the stem inwardly of the collar 20, there is a seat collar 21, the connection between the two being steam tight. This collar is formed with a conical seat 22 toward the collar 20, and the latter 50 is provided with a suitably formed valve face to engage snugly therein. The collar

20 may be formed of brass or other suitable metal, while the piston and collar 21 may be formed of steel. This obviates the expense of fitting a facing on either valve or seats. 60 A port channel 23 is formed in the outer face of the flange 14 next the boiler shell, opening on the interior of the cylinder, communicating with which there are suitable openings 24 through the shell and flange base of the 65 packing box. Leading to these openings there is a suitable pipe 25, having communication with the interior of the boiler at 26, a normally open cut-off valve 26 being interposed adjacent the boiler outlet. The pipe 70 25 has a blow-off extension 28, normally closed by the valve 29. It will thus be seen that the pressures on each side of the piston 17 are normally balanced, and the piston is free to lie at that limit of its movement 75 where left by the movement of the collar 21 under inward movement of the stem 11 into the boiler. In this way there will be practically no wear on the cylinder and engaged part of the piston, owing to the rarity of 80 the use of the latter.

When it is necessary to renew the packing in the box 12, the valve 27 is closed and the one 29 opened. The pressure on the outer end of the cylinder 13 being thus relieved, 85 the piston 17 is forced by the direct boiler pressure of steam along the cylinder engaging the valve collar 20, which is in turn carried into a snug seat in the collar 21, thus closing communication securely through the 90 piston and around the stem 11. The packing rings 18 being of the proper type and operating properly, passage of steam therearound is prevented, regardless of the position of the stem 11. Should a small amount 95 of steam escape, however, to the outer end of the cylinder, it will have free passage to the atmosphere through the valve 29. The packing in the box 12 may then be renewed while full pressure is on the boiler, without 100 liability of injury to the workman, or interference with the operation by steam blowing through the box.

From the foregoing, it will be seen that 105 there has been provided a structure in which the piston or packing element 17 under normal conditions lies out of packing relation with the rod 11, the rod moving loosely through the piston and the latter practically standing still due to the fact that the pressure on the opposite faces thereof balance 110 the same within the chamber formed by the

cylinder 13, this being due to the fact that provision has been made for admitting fluid to the chamber on opposite sides of the piston. The construction is such that a pre-ponderant fluid pressure may be created on one of the faces to cause the piston 17 to enter in packing relation to the rod so that the main packing may be renewed. In the illustrated embodiment, this is produced by causing the piston to engage with the seat or shoulder on the rod 11, but, of course, other packing relations between the fluid-operated packing element and the rod are within the scope of this invention.

The present arrangement permits the main packing to be renewed during the reciprocations of the rod, and, after such operation, the auxiliary packing may be caused to assume its normal ineffective position.

What is claimed is:

1. A packing box, a cylinder connected thereto, a stem slideable through each, a seat element fixed on the stem adjacent the packing box, a piston slideable in the cylinder in steam-tight engagement therewith and loosely engaged around the stem, means to make a steam-tight junction between the piston and seat element when they are pressed toward each other, means to balance the pressure on opposite sides of the piston normally, and means to relieve pressure on one side at times.

2. A device of the class described comprising a packing box, a stem movably engaged therethrough, a cylinder concentric with the stem extending inwardly from the box, a slideable piston in steam-tight engagement within the cylinder and loosely engaged around the stem, an annular seat element on the stem between the piston and box, means for making a steam-tight closure of the passage through the piston when the latter is forced toward the said seat element, means for forming communication between the space on each side of the piston, and means for relieving pressure at the side of the piston toward the box.

3. In combination with a rod and its packing, an auxiliary packing member, means for producing equal fluid pressure on opposite faces of said member to cause said member to lie normally out of packing relation with the rod, and means for producing a preponderant fluid pressure on one face of said packing member to cause the latter to enter into packing relation with the rod.

4. A device of the class described comprising a packing device, a chambered member at its inner side, a movable member engaged through the packing device and chamber, an auxiliary packing device in the

chamber operative under unbalanced fluid pressure thereon, means normally causing balanced pressure on the auxiliary packing device, and means to cause unbalanced pressure on the auxiliary packing device at will.

5. In combination with the rod and its packing, an auxiliary packing for use during the renewal of the main packing comprising a piston through which the rod may move, said piston being normally out of packing relation to the rod, a chamber in which the piston is movable, said chamber having provision on opposite sides of the piston for admitting fluid thereto to balance the pressure on the piston, and means for cutting off the fluid supply on one side of the piston so that preponderant pressure will be created on the other side to cause the piston to establish packing relation with the rod.

6. In combination with the rod and its packing, a cylinder surrounding said rod, a piston slideable in the cylinder in steam tight engagement therewith, and having the rod movable therethrough, a seat formed at one end of the piston, a seat element rigidly secured to the stem and a sliding collar loosely arranged on the stem and having seats, one of which is adapted to engage with a seat element on the valve stem and the other of which is adapted to engage with the seat on the piston.

7. In combination with a rod and its packing, an auxiliary packing embodying a packing element on the rod, a packing element through which the rod is loosely movable, and separate manually-controllable means operable at will to effect coöperation between the auxiliary packing elements.

8. In combination with a shell or a boiler or the like having an aperture, a packing about said aperture, a rod movable through the packing and the aperture, a cylinder projecting from the inner wall of the shell about the aperture and having its free end open, a piston slideable within the cylinder in steam tight engagement therewith and having one face thereof exposed to the pressure at the open end of the cylinder, a seat on the opposite face, a seat on the rod between the packing and the piston, and a manually controllable communication between the shell and the cylinder at a point in the latter between the packing and the piston.

In testimony whereof I have hereunto set my hand in presence of two subscribing witnesses.

GEORGE L. PHILLIPS.
